Primary Examiner — Messina L Smith*Assistant Examiner* — Aram Kwon(74) *Attorney, Agent, or Firm* — Oppedahl Patent Law Firm LLC(57) **CLAIM**

The ornamental design for an electronic device, as shown and described.

DESCRIPTION

FIG. 1 is a front view of an electronic device showing the new design;

FIG. 2 is a back view thereof;

FIG. 3 is a top view thereof;

FIG. 4 is a bottom view thereof;

FIG. 5 is a right side view thereof;

FIG. 6 is a left side view thereof;

FIG. 7 is a front, left side, bottom perspective view thereof;

FIG. 8 is a back, right side, top perspective view thereof;

FIG. 9 is an enlarged view of the portion of the electronic device shown within the area designated as 9 in FIG. 5;

FIG. 10 is an enlarged view of the portion of the electronic device shown within the area designated as 10 in FIG. 7; and,

FIG. 11 is an enlarged view of the portion of the electronic device shown within the area designated as 11 in FIG. 8.

The broken lines encircling portions of the electronic device in FIGS. 5, 7, and 8 and illustrated in enlarged views in FIGS. 9, 10, and 11 form no part of the claimed design. All

(Continued)

other broken lines depict portions of the electronic device that form no part of the claimed design.

1 Claim, 6 Drawing Sheets
